DECORATIVE GRILLEWORK

Robert Porter Hooton, 1511 Marble Ave. NW,
Albuquerque, N. Mex.

Filed Dec. 27, 1965, Ser. No. 432

Term of patent 14 years

(Cl. D13—1)

Fig. 1

FIGURE 1 is a face view of a decorative grille which is made so that either side can be used as the face side.

I claim:

The ornamental design for a decorative grillework, as shown and described.
